UNITED STATES PATENT OFFICE.

ROBERT W. BARKER, OF PROVIDENCE, RHODE ISLAND.

ART OF MANIPULATING STRANDS OR YARNS.

Original application filed August 13, 1920, Serial No. 403,255. Divided and this application filed July 3, 1922, Serial No. 572,618, and in Canada July 25, 1921.

This invention relates to an art of manipulating filaments, yarns or threads, for instance for the purpose of tying a knot, or for forming a component loop or bight of a knot. While the invention contemplates performing the operations of which it consists with the aid of any instrument adapted to the purpose, preferred instruments in a form particularly adapted for use as hand implements for spoolers and other tenders of textile machinery, and adapted in this use for the rapid joining of yarn or thread ends by knotting them together are herein illustrated for aid in explaining the method or art of tying a weaver's knot and other forms of knots useful to workers in textiles, and according to this invention. I do not herein claim these instruments, which are the subject of my application Serial No. 403,255, filed August 13, 1920, of which this application is a division.

I am aware of ancient and numerous practices and instances of the devices used to form yarns or threads into a knot; such practices or devices have been successfully employed by net makers and weavers, in netting machines for making fish and other nets, in book-sewing machines, in harvesters and grain binders, in knitting machines, and machines for tying-in or drawing-in warps; in warping machines, and for use as hand implements for winder or spooler, loom or spinning-machine attendants. It will therefore be understood that the art or procedure of this invention is applicable to many different specific industrial uses, for instance, to improve the knotting practices heretofore relied upon in the above-mentioned and other arts in which arrangement of strands or cordage in bights or the formation of textile cordage knots is a part of the useful or essential operation.

So far as I am aware, the prior art handling and manipulation of the strands or cordage [hereinafter often referred to for convenience as yarn] for the general purposes mentioned has been limited to well-known ways of tying knots by hand, or to the function of certain instruments which may be characterized broadly as of two classes only, i. e., those comprising mutually movable grippers and tweezers and fixed or movable points by which the yarns are manipulated to form the bights of the knot formation sought to be made; and second,

those comprising rotary tying bills and adjunctive mechanism such as static and movable guides and movable take-up or knot-setting means, either type of device including means to sever the yarn acting co-ordinately with the formation of the knot or concatenation of yarns.

For lack in the prior art of appropriate ways or steps of manipulating the yarns or strands to tie them together, the practice has been to manipulate the strands in such a way as to permit the operation to be performed by the available instruments, all of which, so far as I am aware, have serious disabilities inherent in their necessary construction. When it is attempted to form the loops and bights of a knot by separately movable instruments or grippers imitating the action of the human hands, the mechanism required to operate the yarn-handling instruments proper is necessarily bulky and extraordinarily complex. Many arrangements of mechanism which will form interlocking bights or loops of two or more yarns can not be made operative to tie knots usefully because it is impossible to design the mechanism in such a way as to leave any free passage for taking the formed knot off of or out of the instruments which act to form it. This has been a limitation also applying to the ingenious rotary tying bill, which may be operated to form upon itself many theoretical arrangements of loops and bights corresponding to useful knots, but which in few instances is capable of being stripped of the formed knots. These instruments, however, have been employed of old and common knowledge for the formation of the seamstresses' or spooler's knot, with respect to which the adjunctive severing means, stripping means, and take-up means, as well as the mechanism for rotating the tying bill, can be reduced to practicable compass.

A principle object of the invention is to provide a new art or method of handling yarns to create yarn-formations or convolutions adapted to be set up into completed knots of a useful character.

This invention comprises a mode of forming knots characterized by moving an active or carried strand or strands in such a way as to convolute the carried strand about itself, or about itself and another passive strand, in a formation capable of mere rearrange-

ment or upsetting under applied tension into that interarrangement of mutually-interlocked bights, loops and runs of the strand or strands of which a knot of the desired 5 type consists.

In the case of the spooler's knot, the strands are parallel throughout the knot, and the knot may be regarded as a single convolution of one double strand. All of 10 the other forms of two-strand knot known to me I have found capable of being formed by the preliminary convolution of one strand only in respect to another strand held in relatively fixed relation to the locus of the 15 preliminary convolution of the active or carried yarn, and this invention includes a mode of positioning, convoluting, manipulating and severing the strands respectively to produce useful knots by the convolution 20 of an active about a passive strand.

One consequence of forming knots intended to unite two or more strands in this way is to enable a knot of the desired type 25 to be tied by operations on the static or passive yarn consisting of no more than appropriate positioning, the active or carried strand only being subjected to manipulation for forming the preliminary convolution. Another consequence is capacity to 30 perform the operations without limitation by the presence in the formed convolution of the instruments by which it is formed, the operations being capable generically of being performed by a single carrier for the 35 end of the active or carried strand discontinuously associated with its operating means, and therefore capable of permitting the loops and bights of the preliminary formation to be withdrawn freely from the 40 instrument by which they are formed. Other consequences are to permit any relatively complex knot, e. g., a weaver's knot or a square knot, to be formed in relation to a static or passive strand positioned on both 45 sides of the place of the knot, and held during formation of the knot to permit severing of the waste ends close to the formed knot; to permit waste ends of both component 50 yarns of the knot to be severed by the same instrument, if desired, in succession; and particularly, to enable the knot so formed to be tied by devices requiring for applying the yarn to them to be tied movements of the utmost simplicity, capable of execution 55 by machine or by unskilled hands.

I shall explain the invention, with the aid of the accompanying drawing, in connection with mechanism specifically adapted to work upon two yarns to join them in the 60 well-known weaver's knot, and adapted as a matter of design and construction of the parts to be used as a hand implement attached to the hand of the user, and capable of tying perfect weaver's knots, including 65 setting up the knot and severing the waste

ends close to the knot in an improved manner.

Fig. 22 illustrates a later stage of the operation of Fig. 21. 120

Referring now to Figs. 1, 2 and 3, the working parts of the instrument may be erected on any suitable handle or frame 1, which may have eyes 2 for an attachment strap 3 adapted to pass back of the left hand. The handle 1 and its attachments supporting the moving parts are hereinafter referred to as the frame. 125

The upper part of the frame extends at 130

- 4 toward the back of the hand and is there provided with an eye 2, Fig. 2, for the upper end of the strap 3. The top of the frame 1 and the part 4 may be flat at 5 to 5 provide a seat for the attachment of certain of the working parts. Opposite the extension 4 a curved bracket or integral lug 6 is provided at 7 with a bearing for one end of a short transverse shaft 8.
- 10 The frame 1 also includes an integral or attached vertical bracket 9 having a vertical face defining a plane *a*, Fig. 2, and having a tubular rearwardly extending bearing boss 10 for the rear end of the shaft 8. The bracket 9 may be cupped rearwardly toward boss 10 and cut away at 11 leaving arms 12.
- Concentric with shaft 8, bracket 9 and arms 12 support a raceway 15 for actuator means for a yarn carrier presently mentioned. Preferably at least 180° to 270° of the raceway 15 is concentric with the shaft 8, and is provided with an annular slot 16 Figs. 5, 6 and 8, for a carrier driver 17 comprising a segment fitting in the slot 16 and fast to a hub 18 bearing on the shaft 8. The circular parts of the raceway 15 may comprise two L-shaped members 15^a and 15^b, Fig. 20, attached together and defining between them a channel 19 for a contacting series of round steel balls 20 too large to fall out through the slots 16. With the exception of the space occupied by the segment 17 and a yarn carrier presently mentioned the series of balls 20 occupies the entire length of a curved channel connecting the ends of the circular part of the channel 19. Preferably the circular part of the raceway 15 and the channel 19 may, as shown, be so as to leave room for motion through about 180° of the circular part of the path of the balls 20 and for the carrier driver section 17, the extent of this motion being limited by stops 49, 49, for sector 17 one or both of which may be adjustable, so that the series of balls may be moved through about 90°, more or less, of the raceway 15. Continuations of the channel 19 will presently be described.
- The actuator segment 17 may be operated by hand in any convenient manner. For instance, as best shown in Figs. 2 and 3, the bracket 6 may carry a short shaft upon which a thumb lever 26 having at its inner end a shackle 27 is pivoted. Shackle 27 is connected by a link 29 to shackle 30 bearing on a shoulder screw 31 set in segment 17. A downward stroke of the thumb lever 26 therefore drives the segment 17 counter-clockwise as viewed in Figs. 3 or 6. This motion is used for the primary actuation of all of the moving parts.
- Integral with or attached to the hub 18 of the sector 17 cams or linkages for instance severally controlling the timely operation of the yarn severing means and the yarn setting up and stripping means complete the driving devices for the necessary adjuncts for forming the selected kind of knot.
- Let it be supposed, for an instance only, that the yarn carrier is arranged to be driven in a path adapted to take the end of yarn A, Fig. 12, of a pair of yarns A, B, in a convolute path in respect to another of the pair of yarns, such as to pass this end around a bight of the other yarn B and through the loop of the active yarn A formed by the first part of its motion. This produces the same result as the familiar series of manipulations or hand method of forming a weaver's knot (Fig. 17). See Fig. 12, as a consequence of the motion of yarn A about a bight *b* formed in a yarn B. By the hand method the yarn B would have been laid upon the operator's thumb, the yarn A laid across it; the end of the yarn B brought back to form the bight similar to the bight *b* of said figure, and the end of the yarn A then moved in the direction of the arrow heads on so much of the path *a* as is shown in full lines.
- The above described devices actuated by the thumb lever 26 can be arranged to reach the result of these ancient hand operations by the following expedients:
- The channel 19 is diverted through a tangential extension 40 of the raceway 15 and inclined to the rear as best shown in Figs. 4 and 8. The extension 40 may be a separate piece of metal from the remainder of the raceway 15 having in it, see Fig. 6, a preferably rectangular channel 41 continuing the channel 19. The channel 19, 41 is further continued by separate semi-circular raceway, see Figs. 4 and 6, preferably made as a milled channel of rectangular cross section in a two-part block 42 integral with or continuing the piece 40 as illustrated in Figs. 4, 8 and 11. The channel in block 42 is upwardly continued upon a curve of smaller radius but lying in the same plane by a channeled piece 43; the parts 42, 43, may be attached to or formed integral with a block 44 having squared faces one of which supports a tangential way 45 beginning at an inwardly curved portion 46 and ending at the lowest part of the circular raceway 15. Referring to Fig. 6, the way 45 has its left hand end 46 as shown in said figure in position to communicate with the left hand end of the curved channel 43 shown in Fig. 8. The way 45 may be mounted in a channel or hole in the block 44 in any suitable manner. The portion 46, as best shown in Fig. 8, is exteriorly free from contact with the adjacent parts of the curved channels 42, 53 and may have rounded corners to prevent chafing of yarn loops drawn into contact with it.
- The channels 42, 43 are open on the inner faces of the curves which they define for the

passage of a yarn end moving in the channel. One way of doing this is to provide a cut or saw gate 55, see Figs. 7, 8, and 11, entering the ball channel throughout the 5 inner faces of the sections 42, 43 and 45 of the raceway.

It will be evident that when the sector 17 stands against the lower stop 49 a particular place in the chain of balls 20 occupies a 10 particular position at any given point of the raceway, and that motion of the sector 17 toward the upper stop 49 will cause this place in the chain of balls to traverse the convolution represented by the parts 40, 42, 15 43 and 46 of the way or race for the balls.

I employ this motion, whatever the form of the convolution through which the chain of balls moves, to carry the end of the yarn in a path taking the carried yarn through 20 the convolutions of an unformed knot.

For this purpose there is inserted in the chain of balls at an appropriate place a 25 yarn carrier 60, Figs. 9 to 11, which may comprise a short section of a metal bar having a cross-section conforming to and loosely fitting in the channels of the ball race or way, and having spherical or spheroidal ends 61 abutting against and adapted to be driven by and to drive, depending upon the 30 direction of motion, the adjacent balls 20 of the series of balls. In order to accommodate the carrier 60 to the curves of the convolutions through which it is carried the intermediate faces of the rectangular solid 35 constituting this carrier may be concave as shown at 62, 62, in every direction, the curvature of the concave being sufficient to enable passage of the carrier at the place of shortest radius in the convolutions 40 through which it is driven. The carrier is made effective to receive and move a yarn end by the provision in it of a yarn receiving mouth or hook 64.

By reason of the angular cross section of 45 the channels or ways in which the carrier 60 travels the opening of the mouth 63 will always face in the direction of the same face of the channel.

The mechanical transmission represented 50 by the sector 17 and the series of balls including the carrier 60 working in an endless channel is an instrument peculiarly effective for the purpose in mind. There is little back-lash or lost motion when such a 55 chain of balls is sought to be reversed; the motion absorbs little power, is easy and positive, despite the necessary irregularities of the parts. But most importantly, the motion is transmitted to the carrier in such a manner that the transmission means may be 60 parted anywhere for the passage by it of a yarn, the balls yielding through their small back-lash to permit passage through their series of the yarn at any desired point. The 65 series of balls including the carrier and their

driver means 17 may therefore be regarded as an instrument for convoluting a yarn in any desired series of loops or turns and possessing the unique advantage of adaptability to pass an enclosing bight or loop across 70 itself at any point. In other words, any element of a knot or unformed knot, thread crossing, convolution, or cincture of yarns may not only be formed by such an instrument, but also be entered upon and removed 75 from it with complete disregard of limitation by the position of the instrument itself in respect to affording permission for the passage by it of the enclosing loop or bight 80 of yarn.

It will be observed that having provided a conductor or way for the balls and the carrier interspersed in the series of balls, it is only necessary to provide for breakage across of the conductor or way at such points 85 as it is desired to pass a yarn, a bight, a loop, or even a formed knot through the driving connection represented by the balls. And when it is desired that the carrier should carry a yarn end, it is necessary only 90 to open laterally (as at 55) the proper part of the way or channel to provide passage room for the yarn end.

As shown in Fig. 8 for the purpose of making the particular knot selected for illustration, the ball channel or way is broken across at three places 56, 56^a, and 56^b, preferably lying in the same horizontal plane and thereby being adapted to admit passage of a straight run A of one of the yarns to 100 be knotted together to cross the series of balls at three places.

The position of the stop 49 for the driver 17 is such as to bring the mouth 63 of the carrier 60 into coincidence with the cut or 105 opening 56 when the carrier 17 is at the lower end of its stroke and when the thumb lever 26 is at the upper end of its stroke.

Suppose a yarn B to be laid in a diagonal position across the face of the convolution 110 of the way at the parts 42, 43. If then the tense run of yarn A is entered in the alined cuts 56^a and 56^b, passing through the chain of balls in each of these cuts, the yarn B will be drawn inward through the plane of 115 the curves 42 and 43.

The yarn A where it enters the cut 56 will be received in the mouth 63 of the carrier 62. Now let us first cut the yarn A at the point c' and then swing the driver 17 120 upwardly. The cut end a' will move in the direction of the arrow heads, referring now to Fig. 12, through the portion x' of the path x, passing to the right of the yarn B, 125 passing round the bight b of the yarn B, and passing downward through the loop of the yarn A formed by the downward motion of the trailing end of the yarn A and left in the space between the segment 42 of the ball race and the end 46 of the section 45, 130

as shown in Fig. 12 at c^2 . This completes the unformed knot, the end a' of the yarn A pulling out of the carrier 60 on the continued passage of the carrier 60 through the portion 45 of its track or way. There is nothing to impede the removal of the formed knot, a tug on the yarn A removing the yarn formation so made from contact with the means for making it through the 10 cut or passage 56 ^{a} . In practice, the end of the yarn B may be cut at c^2 , preferably after cutting the yarn A at c' . As indicated in diagram in Fig. 12, preferred steps in the operation comprise cutting the yarns A and 15 B successively at c' and c^2 ; this may be done by a single shear blade 155 first cutting one and then cutting the other.

The adjunctive devices for positioning the 20 yarns to be tied, for severing the yarn as an incident of tying, and for setting up and stripping the formed knot from the remaining devices, may be of any desired kind, for example those described and claimed in my said application, Serial No. 403,255, and 25 herein shown only to identify a preferred instrument for the practice of the method or art herein claimed. The devices for forming a weaver's knot shown in the drawings operate to tie the knot by the particular motion 30 diagrammed in Fig. 12. But it will be understood, as hereinafter explained, that the devices employed are in principle adapted to perform a similar duty in connection with operation of my improved implement for 35 carrying one or more ends of yarn into the desired convolution of any type of knot.

Referring now to Figs. 1, 2 and 3 suitable static and movable guides are provided 40 for the primary positioning of a pair or more of yarns, such as the exhausting end and the preceding or fresh end of the winding and the unwinding yarn, which the operator has frequently to tie together. The drawings illustrate a preferred type of 45 guides adapted to receive two yarns, or two groups of yarns, and to conduct them into the positions of the yarns A, B, illustrated in Figs. 11 and 15.

In the preferred form shown, an upwardly projecting central member 75 suitably attached to the bracket 9 defines a vertical plane substantially parallel with axis 8. This separator member preferably has an upper inclined edge 77 extending forwardly to a point 78, Fig. 2, and thence downwardly and inwardly toward the axis 8 (see Fig. 3) to a free bifurcated end 80, 81. The main body of the member 75 is centrally cut away, leaving a central tine the lower end of which is turned up into a hook 83, Fig. 3, facing the raceway 15. The position of this part is such that a yarn passing down the right-hand face of the member 75, as seen in Figs. 1 and 3, will come to rest in the hook 83 and be deflected to the right by the ends

80, 81, thence slip off the end 81 and pass to the left, in front of the block 44 and in front of the curve 42, finally reaching a position extending downwardly from the hook 83 into a depression 85 formed in the 70 frame 1.

The passage of the yarn B in this direction is guided by the periphery of the channel 15 and by a guide 86, Figs. 2, 3, 4 and 5, ending in a point 87 in front of the hook 75 83 and in the plane of the tine 82. The guides 86, 87 and the surface 88 of frame 1 lift the yarn B away from the volute 43, and so prevent this yarn from entering the channel 56 ^{b} .

The rear end of the run of the yarn B 80 engaged in the instrument bottoms in the angle of the guide 75.

Referring to Fig. 1 when the yarns A and B are put into the instrument the yarn A is 85 guided in respect to the remainder of the device on the left-hand side of the member 75, which separates the yarns A and B. Cooperating with the member 75, and stationary while performing the function of 90 guiding the yarn A, I provide guiding surfaces attached to or forming a part of a yarn take-up and knot-setting instrument 100, best shown in Figs. 2 and 3, comprising a lever pivoted on a vertical stud 101, lying 95 parallel with the member 75 when closed, and under tendency to open from a spiral spring 102 coiled about the vertical stud 101. Projecting into the space between the take-up and guide 100 and the member 75 a vertical fin 103 serves to guide the yarn A out of contact with the spring 102. The forward 100 end of the take-up 100 is turned inward toward the member 75 and extended upward to provide a slope 105 and a point 106, serving to guide the forward end of the yarn A against the left-hand surface of the tine 82 until the yarn A passes the tip of the hook 83 and the tip 87 of the guide 86. The tip 87 is closely adjacent to and near the channel 56 ^{b} , see Fig. 3.

Slope 105 ends in hooks 110, Fig. 2, respectively formed in the piece of bent metal constituting the lever 100, and in a cap 111 having a channel in its inner face and attached at 116 to the lower part of the outer end of lever 100, and serving as a housing for a clamp blade 112 having a movement therein limited by the end of a bell-crank lever 140, working in a slot 114. The clamp blade 112 is provided with an inwardly rounded hook 115 conforming to the hooks 110 and adapted to clamp yarns entering the hooks 110 on motion of the blade 112 to the left of Figs. 2 and 5.

As shown, the stud 101 may be formed with a head 117, and be firmly seated in a lug 118 of frame 1.

The take-up lever and clamp are preferably operated as follows: Fin 103 is down-

wardly prolonged to provide a pivot-pin 120 taking into a slot 121 in arm 122^a of a two-armed slide 122, see Figs. 2, 3 and 4 having a bearing in the lug 123 of the frame 1. The right-hand end of this slide is pivoted at 124 to a lever 125 pivoted at 126 to a lug 127 of the frame 1. The upper end of the lever 125 carries an anti-friction roll 128 in contact with a suitable cam 129 mounted on the shaft 8. Lever 125 is also provided with a pin 130 adapted to engage a notch in a latch 131 pivoted at 132 on channel 15. The latch 131 thus locks the lever 125 and slide 122 in position to hold the take-up lever 100 closed, as shown in full lines in Fig. 2. This occurs when the thumb-lever 26 is lifted prior to operation to the position of Fig. 3.

The clamp 112, 115 etc. is arranged to be operated as a consequence of release of the lever 100 by the bell-crank lever 140 Figs. 2 and 3, pivoted on the under side of a lug 141 of the lever 100, said bell-crank lever having one arm engaged through 25 a hole in blade 112, and one arm furnished with a depending pin 142 sweeping the surface of a cam sector 143, best shown in Fig. 2, which sector may be provided with a notch 144 to limit the outward sweep of the take-up arm, and be suitably attached to frame 1. A light spring about the pivot 140 serves to keep the follower pin 142 on the cam 143.

The take-up arm is released at the proper 35 time in the operation by a striker 145 fixed to the hub 18, and adapted to move the latch 131 near the end of the stroke of the thumb-lever 26.

The instrument is in condition to receive 40 two yarns or groups of yarns A and B to tie them together in a weaver's knot when closed into the position shown in Figs. 1 and 2; the thumb lever being elevated. In this condition a pair of yarns may be swept 45 by the operator rapidly into the flaring passages between the point 106 and member 75, and the member 75 and the channel 15 respectively, the point 78 of the member 75 being adapted to enter between twisted 50 yarns and separate them.

The yarn B sweeps to a final position from the angle within separator 75 to hook 83, to notch 85. The yarn A sweeps to the left of member 75 and under the bent end 55 of the member 75. Under stress of the slope 105, the yarn A now slips under the tip of the hook 83 and the tip 87 of the guide 86 and into the cut 56, 56^a, 56^b, Figs. 4 and 8, in the convoluted ball race. At 60 a point between the curve 42 and the hook 83 (see Fig. 11) the yarn A engages the yarn B and carries it inwardly in the bight b, see Fig. 12. In the lateral sense, the motion to the right of the yarn A in the 65 cut 56 ceases upon engagement with the

mouth 63 of the carrier 60, standing at this part of the ball-race. But at the cuts 56^a and 56^b the yarn A is free to sweep through the series of balls, and in doing so bends the yarn B as shown in Figs. 8 70 and 12.

The yarns A and B are now cut in the proper order of sequence by a single cutter 155 operating coordinately with the motions of the carrier 60 to begin the convolutions 75 of the knot. Blade 155 is pivoted on the inside face of bracket 9 at 156, Fig. 3, and may be a shear blade cutting downwardly against a fixed ledger-blade 157, Figs. 2, 3 and 12, mounted on the inner face of bracket 9 with its upper sharpened edge near the yarn A at its point of rest. The point of rest for yarn B is slightly above the edge of ledger blade 157. Closing down of shear blade 155 will thus cut the yarn A 85 first at c¹, Fig. 8, and thereafter cut the yarn B at c², Fig. 8. The operation of blade 155 is arranged to take place in stages separated by a definite movement of the carrier 60, the severing of yarn A occurring 90 during the first part of the motion of the carrier 60, as soon as it has engaged yarn A in its mouth 63, and the severing of yarn B occurring after the cincture or convolution of the knot is well forward, just before the knot is ready to be set up by sudden motion of the take-up 100. As shown the blade 155 is worked by a pitman 160 pivoted to the blade at 161 and to a crank-pin 162 on hub 18 fast on sector 17, in integral with the cam 129 and driver 17. The yarn A is thus cut after being grasped by the carrier 60, but the yarn B is held from pulling out of the position in respect to the motions of the end of yarn A until 105 the end of yarn A has made the motions indicated in Fig. 12. The cut end of yarn A trails behind the carrier 60 through the curve 42, and the held end passes in the slot 55. When the carrier 60 reaches the 110 part 46 of the ball race, the yarn B is severed and the take-up 100 released.

This first clamps the yarn A in the clamp 110, 112, and then pulls the formed knot out of all engagement with the mechanism, the 115 end a' of yarn A pulling out of the end of channel 46 with enough tension firmly to set up the knot, which is formed in the free central space between the curves 42, 43.

Referring now to Fig. 13, the weaver's 120 knot shown in Fig. 17 may also be made by other motions than those following the convolutions of the convoluting instrument explained in connection with the machine figures. With appropriate changes in the 125 motion (which may be practiced by machine by changing the direction of the bent channels) the yarns A and B may be laid across each other, for instance as shown in Fig. 13, and the carried end caused to travel in 130

the path x^2 , but now in the opposite direction as indicated by the arrow-heads in the figure. The yarn A having been severed at c' , the end a' may be carried inwardly and upwardly to form the loop x^3 , downwardly and outwardly between the yarns A and B at x^4 , and thence inwardly and upwardly over itself and under the yarn B at x^5 and through the loop x^3 , as shown. As before, 10 a tug on the end of the yarn A will not set up a weaver's knot.

A somewhat different series of motions for tying a weaver's knot is shown in Fig. 16, the tying-motion being downward, the carried end (and the carrier 60 of the described instrument) taking the end of the yarn A in the path x^6 , as shown in the figure.

Other arrangements still of the motions producing this knot by motion of the active 20 carried yarn end in relation to the other static positioned yarn will occur to the skilled artisan as corresponding to any of the many different ways in which one yarn may be carried around another yarn and itself to form a weaver's knot.

The mechanism explained in connection with Figs. 1 to 12 may also be employed, with minor changes only, to tie a spooler's knot.

30 Referring now to Fig. 20, a fin 203 is provided to enter between the channel 40 and the volute 43, substantially as shown in said figure, and the stop 205 is arranged to cover the cut 56^b. A sloped guide 206 is also preferably mounted on top of the volute 43. The separator 75 may be discarded.

The yarns A and B are now entered together between the slope 203 and the periphery of the channel 15, whereupon both yarns 40 are guided into the cut 56 and the carrier 60, and through the contacting balls at cut 56^a by the operation of the guide 203, being prevented from catching on top of the volute 43 by the guide 206, and being held forward 45 in front of volute 42, 43 by the stop 205. On operating the carrier, the spooler's knot is formed in the manner illustrated in Fig. 22, is set up by motion of the lever 100 in the direction of the arrows in Fig. 21 and Fig. 22, and the cut ends, severed by the shear blade 155, are withdrawn from the channel-piece 46 by the motion of the take-up 100.

The motions made by the yarn, for comparison with the other figures, are diagrammed 55 in Fig. 14. They comprise carriage of the active end of the double strand about a passive portion of the strand and through the loop formed by the motion of the active end.

60 Referring now to Fig. 15, a diagram similar to the other figures is therein shown, explaining the formation of the square knot, Fig. 19, by motions of the active end of the yarn A about the standing or passive yarn B. The adaptation of the mechanism shown for this purpose will be apparent to those

skilled in the art; the carrier is made to follow the convolutions x^{10} , receiving the cut end of the active yarn A at x^{12} , the knot being set and stripped by tension on the active yarn.

When in the claims I refer to motions in complex curves or curves of three-dimensional characteristics, I am to be understood in the ordinary mathematical significance of these words to refer to curves not wholly in two-dimensional space, such as a single plane, but having extent in a third dimension as well.

70 I claim:

1. The art of manipulating strands to tie 80 them together comprising carrying the end of one strand about another held in stationary relation to the locus of the motion of the carried strand.

85 2. The art of tying strands together comprising positioning a passive strand, and carrying an active strand about the position of the passive strand in a convolution adapted to upset under tension into the desired form of knot.

90 3. The art of tying strands together comprising positioning and maintaining in position a passive strand during passage about the passive strand to form the preliminary convolution of a knot of an active strand being carried in a path adapted to lay the active strand in said preliminary convolution.

95 4. The art of tying strands together comprising positioning a passive strand, and carrying an active strand about the position 100 of the passive strand in a convolution adapted to upset under tension into the desired form of knot, and upsetting the convolution into a knot by tension.

105 5. The art of tying strands together comprising positioning a passive strand, and carrying an active strand about the position 110 of the passive strand in a convolution adapted to upset under tension into the desired form of knot, and upsetting the convolution into a knot by tension applied to the active strand.

115 6. The art of tying strands together comprising positioning a passive strand, and carrying an active strand about the position 120 of the passive strand in a convolution adapted to upset under tension into the desired form of knot, and severing the end of the active yarn to permit its carriage singly.

125 7. The art of tying strands together comprising positioning and maintaining in position a passive strand during passage about the passive strand to form the preliminary convolution of a knot of an active strand being carried in a path adapted to lay the active strand in said preliminary convolution, and thereafter tensioning the active strand to upset the preliminary convolution into a knot involving interlocked loops of both strands.

8. The art of manipulating strands to tie them together comprising laying the several strands in a preparatory position, severing one of them to provide a free end, and carrying this end about the other strand in the convolutions of a knot.

9. The art of manipulating strands to tie them together comprising laying the several strands in a preparatory position, severing one of them to provide a free end, and carrying this end about the other strand in the convolutions of a knot, severing the remaining strand, and setting up the knot by strain on the joined strands.

10. The art of manipulating strands to tie them together comprising laying the several strands in a preparatory position, severing one of them to provide a free end, and carrying this end about the other strand in the convolutions of a knot, severing the remaining strand, and setting up the knot by strain predominantly applied to one only of the joined strands.

11. The art of manipulating strands to tie them together comprising laying the several strands in a preparatory position, severing one of them to provide a free end, seizing this end in an appropriate instrument, and carrying this end and the instrument about the other strand in the convolutions of a knot.

12. The art of manipulating strands to form a knot comprising carrying one end of a strand or group of strands in the convolutions of a knot about the other strand or strands, the step including seizing the end by an instrument free to move in said convolutions and moving the instrument throughout such convolutions in respect to the other strand or group of strands, and removing the formed knot from the instrument.

13. The art of manipulating strands or yarns to form a knot comprising laying the yarns in relation to each other, severing the end of one of the yarns, seizing the severed end; carrying the severed end in the convolutions of the knot about the other yarn, and setting up the knot by tension on one of the yarns.

14. The art of manipulating strands or yarns to form a knot comprising laying the yarns in relation to each other, severing the end of one of the yarns, seizing the severed end; carrying the severed end in the convolutions of the knot about the other yarn, then severing the other yarn or yarns and setting up the knot by tension on one of the yarns.

15. The art of manipulating strands or yarns to form a knot comprising laying the yarns in relation to each other, severing the ends of the yarns in predetermined order, seizing the severed end of that one of the yarns first severed; carrying the severed end

in the convolutions of the knot about the other yarn, and setting up the knot by pulling principally on one of the yarns.

16. The art of manipulating strands or yarns to form a knot comprising laying the 70 yarns in relation to each other, severing the ends of the yarns in predetermined order, seizing the severed end of that one of the yarns first severed; carrying the severed end in the convolutions of the knot about the 75 other yarn, and setting up the knot by pulling on that one of the yarns carried about the other.

17. The art of tying knots in yarns or strands comprising positioning one or more 80 of the yarns or strands in the path of and acting on it or them by an instrument traveling in the path of the convolution of the desired form of knot.

18. The art of tying knots in yarns or 85 strands comprising positioning one or more of them in the path of an instrument traveling in the path of the convolution of the desired form of knot; positioning another yarn in and through said path, and seizing 90 and carrying said first mentioned yarn or yarns about the other yarn by the travel of said instrument.

19. The art of tying weavers' knots comprising the steps, laying the yarns or strands 95 to be tied together near each other, forming a bight in one of them, severing the other to provide an end, and carrying this end through the bight, thence between the yarns and around the bight, and through the loop 100 in the carried yarn so provided.

20. The art of tying weavers' knots comprising laying a first and a second yarn to be tied together in crossing relation and near each other, severing an end of the first yarn, 105 passing it around a bight of the second yarn defining the place of crossing, this operation forming an open loop in the first yarn, and passing the end of the first yarn through the loop, and then setting up the knot by 110 pulling on the first yarn only.

21. That method of forming a knot which comprises laying a pair of strands in crossing relation, tensioning one of said strands transversely to produce a bight in the other strand, grasping an end of said tensioned strand by means of a suitable instrumentality, and moving said instrumentality in a path encircling said first and second strands and conforming substantially to the convolution of a knot.

22. That method of forming a knot which comprises laying a pair of yarns in crossing relation, tensioning one of said yarns whereby to form a transverse bight in the other yarn, cutting said first yarn, seizing said yarn adjacent its cut extremity by means of a suitable instrumentality, and moving said instrumentality in a path having a portion thereof lying behind a run of said second 120

yarn, a portion lying in front of a run of said first yarn, and a portion passing through a loop of said first yarn.

23. That method of connecting a pair of 5 yarns which comprises laying said yarns in crossing relation, cutting one of said yarns, seizing the freshly cut extremity of said yarn, moving said extremity about portions of the two yarns in the convolutions of a 10 knot, cutting the second yarn and setting up the knot thus formed.

24. The method of tying yarns which comprises laying a pair of yarns in crossing relation, seizing the extremity of one of said 15 yarns by means of an instrumentality bodily

movable in space, and moving said instrumentality in a three-dimensional path embracing portions of each of said yarns.

25. The method of uniting a plurality of strands which comprises seizure of an end 20 of one strand by a bodily movable instrumentality, moving said instrumentality about portions of a plurality of strands in the convolutions of a knot, setting up said knot and removing said end from said instrumentality.

Signed by me at Boston, Massachusetts,
this twenty-sixth day of June 1922.

ROBERT W. BARKER.

yarn, a portion lying in front of a run of said first yarn, and a portion passing through a loop of said first yarn.

23. That method of connecting a pair of 5 yarns which comprises laying said yarns in crossing relation, cutting one of said yarns, seizing the freshly cut extremity of said yarn, moving said extremity about portions of the two yarns in the convolutions of a 10 knot, cutting the second yarn and setting up the knot thus formed.

24. The method of tying yarns which comprises laying a pair of yarns in crossing relation, seizing the extremity of one of said 15 yarns by means of an instrumentality bodily

movable in space, and moving said instrumentality in a three-dimensional path embracing portions of each of said yarns.

25. ROBERT W. BARKER.

CERTIFICATE OF CORRECTION.

Patent No. 1,612,798,

granted January 4, 1927.

to ROBERT W. BARKER.

It is hereby certified that the above mentioned patent was erroneously issued to the inventor, said Barker, whereas said Patent should have been issued to Edward A. Taft, Trustee, of Brookline, Massachusetts, as assignee of the entire interest in said invention, as shown by the records of assignments in this office; and that the said Letters Patent should be read with this correction therein that the same may conform to the record of the case in the Patent Office.

Signed and sealed this 15th day of February, A. D. 1927.

Seal.

William A. Kinnan,
Acting Commissioner of Patents.
